(57) **CLAIM**

The ornamental design for a hat rack, as shown and described.

DESCRIPTION

FIG. 1 is a front, right and top perspective view of a hat rack including two racks and two bases assembled together showing my new design;

FIG. 2 is rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right and top perspective view of one of the two racks shown in FIG. 1, with the other rack and the two bases removed for clean illustration;

FIG. 10 is rear, left and bottom perspective view thereof; FIG. 11 is a front, right and top perspective view of one of the two bases shown in FIG. 1, with the other base and the two racks removed for clean illustration;

FIG. 12 is rear, left and bottom perspective view thereof; and,

FIG. 13 is an exploded perspective view of the hat rack. The broken lines depict portions of the hat rack that form no part of the claimed design.
